HENRY RIDGEWAY HART, OF MONTCLAIR, NEW JERSEY.

FOOTBALL HELMET.

Application filed January 11, 1922. Serial No. 528,432.

To all whom it may concern:

Be it known that I, HENRY RIDGEWAY HART, a citizen of the United States, residing in Montclair, in the State of New Jersey, have invented certain new and useful Improvements in Football Helmets, of which the following is a specification, reference being had to the accompanying drawing, forming a part hereof.

10 Football helmets have to satisfy widely divergent requirements. Primarily, they are for the protection of the wearer, but in providing this protection care must be exercised lest the means which protect the wearer cause injury to the opponent. Further, a helmet to serve its greatest usefulness must not only yield protection to the top of the head and ears but also to the base of the skull and the neck. Real protection against 15 hard blows can only be secured through an inflexible shell, which can be shaped in manufacture to protect the top of the head and base of the skull and neck. An inflexible shell of this kind, however, may not be 20 placed in contact with the head because of the discomfort and injury which would be caused thereby and it may not lie near the outer surface of the helmet because of injury that it might cause to opponents. In 25 view of these considerations, inflexible members, so far as is known, have never been incorporated in football helmets. The principal object of the present invention, therefore, is to meet all of the conditions outlined above by providing a football helmet 30 which shall be comfortable to the head, safe for opponents, and afford the greatest possible protection to the wearer through the incorporation therein of an inflexible shell 35 shaped in manufacture to protect the head and neck from blows and yet it is to be imbedded in protective coverings of felt or the like. A further object of the invention is to provide in such a helmet a smooth continuous outer covering therefor which shall 40 prevent injury to the helmet and present a comparatively smooth surface to opponents. More particularly, the invention has for its object to provide a football helmet which 45 shall have an integral shell of fiber therein shaped in manufacture to conform to the head, layers of felt on either side of the shell and an outer covering of leather. The invention will be described with greater particularity in connection with the embodied 50

55 ment thereof illustrated in the accompanying drawing, wherein—

Figure 1 is a view in perspective of the improved helmet.

Figure 2 is a view in longitudinal section 60 taken through the helmet and showing its composition in greater detail.

Heretofore, it has been thought impracticable, for several reasons, to incorporate in a helmet an inflexible shell, since no material 65 of suitable properties, such as lightness and rigidity, has suggested itself to any one and because, further, the employment of an inflexible shell has seemed uncomfortable to the wearer and dangerous, both to the 70 wearer and his opponents. It has been found that fiber lends itself advantageously to use as a protective shell in football helmets since in manufacture it can be shaped to the head and is light, rigid and strong. 75 In the broader aspects of the present invention the particular shape of the shell of fiber employed in the helmet may be varied, but in the preferred form this shell will conform to the shape of the top of the head and 80 be extended downwardly at its rear so as to lie over the base of the skull and the neck, such a shell being illustrated at *a* in Figure 2. Starting with a shell of this character, the improved helmet is built up therefrom 85 by lining the shell with a layer of felt *b* of suitable thickness which, in the most approved manufacturing methods, will be of the same general shape as the shell. The outer surface of the shell *a* will likewise 90 be covered with a layer of felt *c* of suitable thickness, which also will, of course, conform generally to the shape of the shell *a*, but this outer layer of felt in the preferred construction will extend below the 95 edge of the shell for an appreciable distance and be shaped to form ear covering *c'*. An inner layer of felt *b'* is stitched to the felt *b* along its lower edge, as indicated at *b*², and extends downwardly in conformity to the 100 downwardly extended portion of the felt *c* to constitute therewith ear coverings, the inner layer *b'* being stitched to the outer layer *c* along the edge thereof by means of stitching *b*³. By this construction it will be 105 evident from Figure 2 that a double layer of felt is brought around the lower edge of the fiber shell *a*, thereby affording substantial protection both to the wearer and his opponents. The inner layer of felt *b* being of 110

suitable thickness for protective purposes will also be of such yielding qualities as to insure conformation generally of the helmet to the head. The outer layer of felt *c* will afford protection against injury to opponents and serve further to cushion the blows on the helmet.

To finish off the helmet in a way which will not only be sightly but will actually afford some physical advantages in use, there is provided a thin covering of smooth leather *d* stitched around the lower edge of the helmet to the outer layer of felt *c* and the inner felt piece *b'* through the stitching *b*³. At the front of the helmet a further finishing cover is provided in the leather piece *e* which extends from the lower edge of the covering *d* around the lower edge of the felt pieces *b* and *c* and up over the inner surface of the inner felt piece *b'* terminating near the line of stitching *b*². This separate piece of leather *e* may be cemented or otherwise fastened in place, but serves as a desirable finishing cover to protect the lower edge of the helmet at a point where it would ordinarily be subject to destructive wear. The smooth leather cover formed as described lends strength and finish to the entire structure and presents a smooth surface

to opponents which is some protection to the wearer in play.

Air vents *f* may be cut through the entire helmet at such points as may be desirable.

What I claim is:

1. A football helmet having an inflexible reenforcing shell of fiber of one piece shaped to conform to the head of the wearer, protective layers of felt on the inner and outer sides of the shell and means to secure the felt in place against displacement. 40

2. A football helmet having an inflexible reenforcing shell of fiber of one piece shaped to conform to the head, an outer layer of felt covering the shell and extended below its edge to form ear coverings, an inner layer of felt for the shell terminating in proximity to its edge, a third piece of felt secured to the inner layer of felt along its edge and shaped to conform to the ear coverings, a line of stitching along the edge of the outer layer of felt to secure it to said third piece of felt, and a covering of smooth leather for the outer layer of felt and secured thereto by said stitching. 45

This specification signed this 9th day of January, A. D. 1922. 55

HENRY RIDGEWAY HART.
